UNITED STATES PATENT OFFICE.

STEFAN SCHNEIDER, OF CHARLOTTENBURG, GERMANY.

BALL-HOLDING RING FOR BALL-BEARINGS.

No. 851,697.

Specification of Letters Patent.

Patented April 30, 1907.

Application filed July 7, 1906. Serial No. 325,100.

To all whom it may concern:

Be it known that I, STEFAN SCHNEIDER, a subject of the Emperor of Germany, and a resident of Charlottenburg, Germany, have 5 invented a certain new and useful Improvement in Ball-Holding Ring for Ball-Bearings, of which the following is a specification.

This invention relates to a ball holding ring for ball bearings.

Under my invention the balls are held apart by securing on two oppositely disposed annuli U-shaped distance pieces preferably stamped of sheet-metal and one series of which is filled with a soft yielding or resilient 15 material such as felt whereby during the use of the ball bearing unnecessary noise and wear are avoided, and on movement of the balls during use equilibrium is quickly attained.

In the accompanying drawings which illustrate the invention Figure 1 shows the improved ball holding ring, the lower half being in side elevation and the front annulus in the upper half being considered as removed with 25 the separating piece in section. Fig. 2 shows in section the two annuli or cages with the balls lying between, the alternate distance pieces being secured on one annulus and the intervening pieces on the other annulus.

As shown, between the two annuli or cage-

rings *a* and *b* are carried the balls *c* which are held apart by distance pieces.

The U-shaped distance pieces *g* are secured to the one annulus *b* in a continuous series while the U-shaped holders *h* are secured to the other annulus *a* and receive filling material *f*. The said holders *h* are secured on the annulus *a* opposite the distance pieces *g* and are adapted to be pressed into the same on mounting the balls *c* in the ring.

It will be noticed that the shape of the distance pieces is such as to enable the felt-holders to accommodate themselves therein.

Having described my invention what I claim and desire to secure by Letters Patent 45 of the United States is:

A ball-holding ring for ball bearings comprising two oppositely disposed annuli or cage-rings having U-shaped distance pieces secured to one annulus and U-shaped holders 50 filled with resilient material secured to the other annulus and adapted to fit into said distance pieces, substantially as described.

In testimony whereof I have signed my name to this specification in the presence of 55 two subscribing witnesses.

STEFAN SCHNEIDER.
